UNITED STATES PATENT OFFICE.

CLARENCE A. HOY, OF BUFFALO, NEW YORK, ASSIGNOR TO PEERLESS HUSKER COMPANY, A COPARTNERSHIP, OF BUFFALO, NEW YORK.

RECEPTACLE-FILLING MACHINE.

Application filed May 29, 1918. Serial No. 237,308.

To all whom it may concern:

Be it known that I, CLARENCE A. Hoy, a citizen of the United States, residing in Buffalo, in the county of Erie and State of New York, have invented new and useful Improvements in Receptacle-Filling Machines, of which the following is a specification.

This invention relates to a machine for partly or wholly filling containers or receptacles such as tin cans with the material which is to be packed or preserved.

It is the object of this invention to produce an improved machine for this purpose in which the receptacle, container or can itself serves as the element which determines the amount of material which is delivered into the receptacle in order to exactly fill the same and to accomplish this by means which are of simple and durable construction and efficient in operation, which are not liable to crush or bruise the contents of the can, which can be readily adapted to fill receptacles of different sizes, which is so designed as to avoid objectionable dripping from the supply means after a can has been filled, and in which the joint or seal between the can or container and the supply means is effected without requiring undue pressure between these parts.

In the accompanying drawings:

Figure 1 is a vertical section of a receptacle filling machine embodying my invention. Figure 2 is a horizontal section taken on line 2—2, Fig. 3. Figure 3 is a fragmentary vertical section of the valve mechanism embodying my improvements, the section being taken at right angles to Fig. 1. Figure 4 is a bottom plan view of this valve mechanism. Figures 5 and 6 are fragmentary sections shown in modified forms of the valve mechanism.

Similar characters of reference refer to like parts throughout the several views.

My improvements are capable of use in a machine which is adapted to fill a receptacle, container or can either wholly with liquid or similar material or to only finish filling of such receptacles. When packing syrup or pulp of vegetables the can is usually filled entirely with this material, but when packing beans or the like it is customary to add a small quantity of tomato sauce or other dressing and when packing fruits and similar material it is customary to complete or

finish the filling of the can by delivering into the same a quantity of brine, syrup or preservative.

1 represents the supply tank or reservoir from which the fluid or semi-fluid material to be packed is drawn for delivery into the container which is to receive the same. This container in this instance is represented as a tin can having an upright cylindrical body 2 and a horizontal bottom 3 while its upper end is opened. During the filling operation this can rests with its underside on a table 4 which is movable toward and from the reservoir or tank and the parts associated therewith.

5 represents an upright supply pipe which communicates with the supply tank and is preferably connected at its upper end with the outlet 6 in the bottom of this tank by means of a coupling nipple 7 provided with a lower internal screw thread engaging with the externally threaded upper end of the supply pipe and an upper external thread which engages the internal thread in the outlet of the supply tank as shown in Fig. 1. Slidable vertically on the lower part of this supply pipe is a bearing head which is adapted to form a joint or seal with the upper edge of the can and also part of the valve mechanism whereby communication is established between the lower end of the supply pipe and the can as well as interrupting communication between these two members.

This bearing head preferably comprises an upper non-elastic plate 8 which is guided on the supply pipe and a lower elastic facing 9 adapted to engage with the upper edge of the receptacle which is to be filled and form a liquid tight joint or seal therebetween. The non-elastic plate preferably consists of metal and is provided with a tubular neck or hub 10 whereby the same is guided on the supply pipe, a leak-tight joint being preferably effected between this hub or neck and pipe by means of a packing 11 surrounding the supply pipe and compressed between the upper end of this hub and a gland 12 connected with this hub.

The bearing head is yieldingly held in its depressed position by means of a spring 13 surrounding the supply pipe 5 and engaging its upper end with a coupling nipple 7 while its lower end engages with the gland 12 of the bearing head. The elastic facing is preferably constructed in the form

of an annular ring and the same is connected with the metal plate of the bearing head by providing the underside of this plate with an annular groove 14 which is undercut or of upwardly flaring or dove-tail shape in cross section so that when the upper part of the elastic facing engages with this groove the same will be of corresponding form and be locked or retained against displacement therein. The opening in the center of the elastic facing of the bearing head forms a port 15 leading from the lower end of the supply pipe to the underside of this facing and to the interior of the can which is engaged at its upper edge by the underside of this facing. The tightness of the joint between the can and the bearing head depends upon the condition of the upper edge of this can and the pressure which is exerted upon by the same by the facing of the bearing head. It has been found in practice that the upper edge of a can is frequently rough, nicked or otherwise damaged which renders it difficult to maintain a tight joint or seal between this can and the bearing head in order to prevent the loss and waste of any of the material which is being delivered into the can. To enable the bearing head to readily adapt itself to variations in the upper edge of the can and form a tight joint therewith without requiring undue pressure this elastic facing is preferably constructed of a core or body 16 of porous material such as sponge rubber and a shell or jacket 17 of non-porous material such as soft solid rubber which is connected with the core or body by vulcanization. A facing thus constructed has more resilience than if the same were entirely constructed of the purest grade of gum rubber and therefore enables the same to readily adapt itself to an irregular edge of the can so as to form a tight joint therewith without requiring undue pressure between these parts and thereby produce a leak proof joint without unduly wearing this facing.

The diameter of the bearing head is sufficiently large to accommodate cans of different diameters, the upper edges of which engage with the outer part of the underside of the bearing head facing according to the diameter of the respective can. The inner part of the underside of this bearing head facing forms a valve seat which is adapted to be engaged by a valve disk 18 which controls communication between the supply pipe and the port of the bearing head and the mouth of the can which is to be filled. This valve disk is preferably constructed in the form of a comparatively thin disk of metal which is arranged horizontally close to the underside of the bearing head and adapted to engage the upper side of its marginal part with the valve seat formed by the inner part of the bearing head facing so as to form a leak

tight joint therewith. The valve disk is of such diameter that the same when arranged axially in the mouth of a can has its periphery only a short distance from the bore of the can and thus nearly covers the mouth of the same. In order, therefore, to adapt this filling machine for cans of different diameters a plurality of valve disks are provided which are of different diameter, each valve disk being suited for a particular size of the can so that by inter-changing these valve disks cans of various diameters can be filled with the same machine. In the larger sizes of valve disks which are intended for filling cans of large diameters the upper side of the valve disk is provided at its margin with an upwardly projecting narrow annular rim bearing 19 for engagement with the elastic surface of the bearing head along a narrow surface only so as to insure proper closing of the port of this valve mechanism but this rim may be omitted and the marginal part of the disk engaged directly with the facing of the bearing head near its port, as represented by the valve disk 20 in Fig. 5.

This valve disk whether of large or small diameter is detachably mounted on the lower end of the supply pipe so as to be immovable thereon when in use and the same also forms part of the means whereby the interior of the can is vented to the atmosphere so as to permit the air in the can to escape and enable the packing material to freely enter the can. For this purpose a supporting disk 21 is arranged horizontally below the lower end of the supply pipe and below the port of the bearing head. This supporting disk is preferably connected with the supply pipe by means of a transverse bridge 22 extending across the lower end of the supply pipe and in the preferred construction, the supporting disk and the bridge are made integrally of cast metal. The valve disk 18 is detachably secured to the supporting disk and bridge by a screw 27 passing upwardly through the central parts of these members. In its upper side the valve disk is provided centrally with a circular recess 23 which receives the supporting disk, this recess being equal in depth to the thickness of the supporting disk so that the upper side of the supporting disk and the adjacent part of the upper side of the valve disk is flush, as shown in Figs. 1 and 3.

The opposing surfaces of the supporting disk and the valve disk are constructed to form a vent chamber between the same, this being preferably accomplished by providing the underside of the supporting disk with an annular groove or recess 24 as shown in Figs. 1 and 3. The valve disk is provided with a plurality of vent openings 25 which are preferably arranged around the axis of the same and each ex-

tending from the vent chamber to the underside of the valve disk so that the interior of the can which is being filled is placed in communication with the vent chamber. 26 5 represents a vent pipe arranged within the supply pipe and tank and terminating at its upper end above the liquid space within the tank while its lower end is secured in an opening in the bridge so that this vent 10 pipe communicates with the vent chamber.

When this machine is at rest the bearing head is held yieldingly in its lowermost position with its elastic facing engaging the valve disk by the spring 13 so that at this 15 time no liquid or other material can escape from the tank through the supply pipe and past the valve. In the operation of filling a can or receptacle the latter is placed upon the table 4 axially in line with the valve 20 disk and then the table is lifted. During this upper movement of the can the valve mechanism remains undisturbed up to the time the upper edge of the can engages the elastic facing of the bearing head, as shown 25 in Fig. 1. Upon continuing the upward movement of the can after its upper edge engages with the elastic facing of the bearing head the latter will be lifted so as to disengage its valve seat from the valve 30 disk, thereby opening the valve and permitting the liquid material to flow from the tank through the supply pipe and port of the bearing head into the upper end of the receptacle, the air in the can during 35 this time escaping through the vent openings, vent chamber and vent pipe to the atmosphere. Only so much material will flow from the tank into the can as is necessary to completely fill the latter so that in 40 effect the can, container or receptacle automatically serves as the measuring instrument whereby the exact quantity of material required to completely fill the can is controlled. After the can has been thus 45 filled the table is lowered together with the can, thereby permitting the bearing head to again lower into engagement with the valve disk under the action of the spring 13 and thereby cut off the further escape of material 50 from the supply tank so that no dripping of the surplus material occurs at the edge of the valve.

Owing to the large area of the valve disk which extends practically over the entire upper end or mouth of the can to be filled any material which has been previously inserted in the can will be pressed downwardly uniformly during the filling operation and then released in like manner 55 when the can is withdrawn from the valve mechanism and permitting the solid contents of the can to spring back into its normal position thereby avoiding crushing or bruising of the fruit which would be liable 60 to occur if a comparatively narrow instru- 65

ment were pushed downwardly into the mass of material which is being packed during the filling operation.

By employing a plurality of vent openings around the axis of the valve disk it is 70 practically impossible to prevent the escape of air from the upper end of the can while the filling material is entering the same. This is due to the fact that the vent openings are sufficiently numerous so that if 75 one or more of them should become clogged by the material in the can a sufficient number of the same will still be vacant or unobstructed to permit the free escape of the air from the can to the outer atmosphere, 80 thereby insuring uniform and complete filling of all of the cans with the material which is to be packed.

By constructing the facing of the bearing head of a core of porous sponge rubber and a jacket of non-porous or solid flexible rubber contamination of this facing is rendered impossible while at the same time forming a leak tight joint or seal between the rims of the cans which may or may not 85 be damaged with the use of comparatively light pressure.

If desired the upper side of the supporting disk 28 in the case of small valves may engage at its marginal part with the underside of the valve seat or face of the bearing head and serve as the valve proper while the associated disk 29 merely serves as a pressure plate for distributing the pressure 90 uniformly over the top of the fruit in the 95 can, as shown in Fig. 6.

While the liquid is flowing from the tank 1 into the upper end of the receptacle which is being filled, some of this liquid also rises in the vent tube 26, but when the filling 100 valve is closed upon withdrawing the receptacle from the underside thereof the liquid in the vent tube will flow into the upper end of the receptacle and fill the space previously occupied in the receptacle by the disk 105 110 115 120 125 130 18 and associated parts, the amount of liquid so delivered by the vent pipe into the receptacle being taken into consideration when designing the apparatus.

As a whole this valve mechanism is exceedingly simple, the same is not liable to get out of order, it can be produced at comparatively low cost and owing to the parts being readily accessible, it is possible to thoroughly clean the same and maintain it in the most sanitary condition.

I claim as my invention:

1. A receptacle filling machine comprising a bearing head having a filling passage and provided on its underside with a valve seat, a supporting disk arranged at the lower end of said passage, and a valve disk arranged with its central part below the underside of said supporting disk and adapted to engage its marginal part with

said valve seat, the opposing surfaces of said supporting and valve disks being spaced apart to form a vent chamber leading to the atmosphere and said valve disk being provided with a plurality of vent openings leading from said chamber to the underside of said valve disk.

2. A receptacle filling machine comprising a bearing head having a filling passage 10 and provided on its underside with a valve seat, a supporting disk arranged at the lower end of said passage, a valve disk arranged with its central part below the underside of said supporting disk and adapted to engage its marginal part with said valve seat, the opposing surfaces of said supporting and valve disks being spaced apart to form a vent chamber leading to the atmosphere and said valve disk being provided with a 20 plurality of vent openings leading from said chamber to the underside of said valve disk, and a bridge carrying said supporting and valve disks and provided with a vent passage leading to the atmosphere.

25 3. A receptacle filling machine comprising a stationary upright supply pipe adapted to communicate at its upper end with a supply of the filling material, a bearing head slideable vertically on said pipe and 30 having a central port communicating with said pipe and a bearing face on its underside the outer part of which is adapted to be engaged by the upper edge of the receptacle to be filled, a spring for holding said 35 head yieldingly in its depressed position, a supporting disk mounted on the lower end of said pipe, and a valve disk arranged with its central part below said supporting disk and engaging its marginal part with 40 the inner part of the bearing face of said head, said supporting and valve disks being spaced apart to form a vent chamber which leads to the atmosphere and said valve disk being provided with a plurality of vent 45 openings leading from said chamber to the underside of said valve disk.

4. A receptacle filling machine comprising a stationary upright supply pipe adapted to communicate at its upper end with a 50 supply of the filling material, a bearing head slideable vertically on said pipe and having a central port communication with said pipe and a bearing face on its underside the outer part of which is adapted to be 55 engaged by the upper edge of the receptacle to be filled, a spring for holding said head yieldingly in its depressed position, a bridge extending across the lower end of said pipe, a supporting disk mounted on said bridge, a 60 valve disk having the central part of its upper side provided with a recess which receives said supporting disk and engaging the upper side of its marginal part with the inner part of the bearing face of said head, the opposing 65 surfaces of said supporting and valve

disks being spaced apart to form a vent chamber and said valve disk being provided with a plurality of vent openings leading from said chamber to the underside of said valve disk and a vent pipe connected with 70 said bridge and extending from said chamber upwardly through said supply pipe to the atmosphere.

5. A filling machine comprising a main reservoir, and a discharge device for controlling the flow from said main reservoir, 75 said discharge device comprising a combination valve, displacement and spreader member, comprising a substantially flat disc, having an annular seating surface on its upper face, a vent tube leading from said combination member for the escape of the air displaced from the can by the flowing in of the liquid, a passage for the liquid from said main reservoir to the upper face of said combination member, and a sealing member having a flat, annular lower sealing surface of considerable extent, said sealing member being vertically reciprocable, and said sealing surface having a portion 80 for engaging the seating surface on the upper face of said combination member, and having a flat, annular seating surface of considerable extent extending beyond said combination member, whereby said discharge member may be used with various sizes of cans without accurately centering said cans with respect to said discharge controlling means, and means for bringing the edge of the can into sealing engagement 85 with said extended annular sealing surface, to lift said sealing member, to permit the flow of liquid from said main reservoir, over said spreader member, between said seating surface and said sealing surface, said combination member being readily detachable and replaceable, whereby displacement discs of various sizes may be used to 90 vary the displacement.

6. A filling machine comprising a main reservoir, and a discharge device for controlling the flow from said main reservoir, 100 said discharge device comprising a combination valve, displacement and spreader member, comprising a substantially flat disc having an annular seating surface on its upper face, a vent tube leading from said combination member for the escape of the air displaced from the can by the flowing in of the liquid, an annular passage member for the liquid from said main reservoir, 105 to the upper face of said combination member, and a sealing member having a flat annular lower sealing surface of considerable extent, said sealing member being vertically reciprocable upon said annular passage member, and said sealing surface having a portion for engaging the seating surface on the upper face of said combination member and having a flat annular seat- 110

ing surface of considerable extent extending beyond said combination member whereby said discharge member may be used with various sizes of cans without accurately 5 centering said cans with respect to said discharge controlling means, and means for bringing the edge of the can into sealing

engagement with said extended annular surface, to permit the flow of liquid from said main reservoir over said spreader member 10 between said seating surface and said sealing surface.

CLARENCE A. HOY.
